UNITED STATES PATENT OFFICE.

MAX SINGELMANN AND CARL BRINKMANN, OF CHICAGO, ILLINOIS.

GAS-BURNER FOR STOVES.

1,192,129.

Specification of Letters Patent. Patented July 25, 1916.

Application filed September 22, 1915. Serial No. 51,910.

To all whom it may concern:

Be it known that we, MAX SINGELMANN and CARL BRINKMANN, subjects of the Emperor of Germany, and respectively residing at 1705 North Park avenue and 1835 Howe street, in the city of Chicago, county of Cook, and State of Illinois, have invented certain new and useful Improvements in Gas-Burners for Stoves, of which the following is a specification.

Our invention relates to improvements in gas burners and more particularly to burners of this class which are adapted to be fitted in stoves.

15 The objects of our invention are to provide a simple, durable and efficient burner which may be easily and quickly fitted in place in any well known type of stove and to so arrange and mount the burner that it 20 may be adjusted to direct the heating jets of gas toward different points within the stove. These and other objects we accomplish as hereinafter described and as more particularly pointed out in the claims, reference being had to the accompanying drawings in which an embodiment of our invention is shown.

In the drawings Figure 1, represents a horizontal section through a stove equipped 30 with our improved burner. Fig. 2, is a fragmentary vertical longitudinal section through a stove equipped with our improved burner. Fig. 3, is a detached perspective view of the burner supporting plate.

35 In referring to the embodiment of our invention shown in the accompanying drawings in detail, like numerals designate corresponding parts.

To illustrate the manner in which our improved burner is fitted in a stove, we have 40 shown in Figs. 1 and 2, sections through a heating and cooking stove in which the oven is designated by 1, the grate by 2, the hot water pipes or water front which is located 45 opposite the oven and in front of the stove by 3, the fire box by 4 and the front, rear and side walls of the fire box by 5, 6, 7 and 8, respectively.

The burner which we preferably employ 50 is of a U-shape as shown in Fig. 1 and consists of two parallel side members 9, a straight transverse member 10, connecting said side members at one end thereof and a curved member 11, extending between and 55 joining the opposite ends of the side members. The side members are preferably of a

hollow square form in cross section and are provided on one of their faces with a plurality of perforations 12, which constitute gas jets. A tubular extension 13, projects 60 from the curved member 11, of the burner and is exteriorly screw threaded and a funnel shaped air mixer 14, is screwed upon said extension as shown in Fig. 1. A gas pipe 15, extending from a source of gas supply 65 is suitably attached to the air mixer.

In fitting our improved burner in a stove, the extension 13 is fitted through an opening in the wall 7 and the air mixer 14, screwed upon its projecting end. Means are provided for supporting the opposite or inner end of the burner which preferably comprises an extensible partition which is fitted in the fire box between the front and rear walls thereof. The partition as shown 75 consists of two plates one of which is wider than the other and which are lapped and fastened in place. The wider plate 16, is provided with a series of holes 17, arranged in a vertical row in any one of which a stud 80 18, projecting from the member 10 can be fitted and a horizontal slot 19 at one side of the row of holes.

As shown in Fig. 1, the lower edge of the fire brick back 20 for the wall 6, of the fire 85 box is curved or rounded and the lower corner 21 of the plate 16, is correspondingly curved so as to fit beneath the same. The narrow plate 22, is provided with a curved projecting lower corner 23, which fits beneath the lower water pipe and an opening which registers with the slot 19, when the plates are in lapping position and through which a bolt 24, or similar fastener can be 90 fitted to secure the plates together. 95

With this improved burner the gas flame can be directed against the oven, the water front or vertically upward as desired, the burner being so arranged that it may be turned or rotated by hand to any position 100 from a horizontal to a perpendicular.

While we have illustrated and described preferred forms of construction for carrying our invention into effect this is capable of a wide range of variation, alteration, 105 modification and change without departing from the spirit of our invention. We therefore do not wish to be limited to the construction herein shown and described, but desire to avail ourselves of all such variations, alterations, modifications and changes 110 as fairly fall within the scope of the ap-

pended claims or may be construed to be within the scope thereof by involving the doctrine of equivalents.

What we claim as our invention and desire to secure by Letters Patent is:

- 5 1. The combination with a stove having walls, of a gas burner arranged horizontally within said stove and having a rectangular loop body and oppositely projecting end extensions, one of which is supported from a wall of the stove and a transverse removable partition also arranged within the stove and having a hole in which the opposite extension of the gas burner seats.
- 10 2. The combination with a stove, having walls, of a gas burner arranged horizontally within said stove and having one end supported from a wall of the stove and a transverse extensible removable partition also arranged within the stove and adapted to support the opposite end of the burner in place.
- 15 3. The combination with a stove having walls, of a gas burner arranged horizontally within said stove and having one end supported from a wall of the stove and a transverse extensible removable partition consisting of two lapping plates also arranged within the stove and adapted to support the opposite end of the burner in place.
- 20 4. The combination with a stove having walls, of a gas burner arranged horizontally within said stove and having a rectangular loop body and oppositely projecting end extensions, one of which is supported from a wall of the stove and a transverse removable partition also arranged within the stove and having a series of holes arranged in a vertical row in any one of which an extension of the gas burner may be seated.
- 25 5. In a device of the class described, the combination with a stove, of a gas burner

having an extension at each end thereof, one of which is mounted in the wall of the stove, and an extensible partition removably fitted in the stove for supporting the opposite extension. 45

6. In a device of the class described, the combination with a stove, of a gas burner having an extension at each end thereof, one of which is mounted in the wall of the 50 stove, and an extensible partition removably fitted in the stove for supporting the opposite extension, and composed of two plates with their sides lapped and bolted to each other. 55

7. In a device of the class described, a hollow loop form gas burner having an extension at each end thereof, an extensible partition for supporting one extension, means for supporting the other extension, 60 one of said extensions being tubular, and means for supplying gas to said tubular extension.

8. The combination with a stove having walls, of a gas burner arranged horizontally 65 within said stove and having a rectangular loop body and oppositely projecting end extensions, one of which is supported from a wall of the stove and a transverse removable partition also arranged within the stove and having a wide plate provided with a vertical row of holes, in any of which an extension of the gas burner may be fitted, and a horizontal slot at one side of the row of holes and a narrow plate adapted to lap upon the 70 wide plate and having an opening registering with the slot and a bolt fitted through the slot and opening.

In testimony whereof we have hereunto set our hands.

MAX SINGELMANN.
CARL BRINKMANN.
